BROOM HEAD OR THE LIKE

Milan J. Mylan, 974 Haverford Ave.,
Pacific Palisades, Calif. 90272

Filed July 12, 1971, Ser. No. 161,407

Term of patent 3½ years

Int. Cl. D4—01

U.S. Cl. D49—21

FIG. 1 is a right-side elevational view of my new design;

FIG. 2 is a left-side elevational view thereof;

FIG. 3 is a top plan view of my new design as illustrated in FIG. 2;

FIG. 4 is a rear elevational view thereof; and

FIG. 5 is a front elevational view of my invention.

The dotted lines showing the handle are for illustrative purposes only and form no part of the claimed design.

I claim:
The ornamental design for a broom head or the like, as shown and described.
